UNITED STATES PATENT OFFICE.

RALPH G. WHITLOCK, OF LOS ANGELES, CALIFORNIA.

PRINTING PRESS.

Application filed June 25, 1925. Serial No. 39,558.

I have invented new and useful improvements in printing presses, which appertain generally and are particularly adapted for use in printing indicia on matter to be mailed in lieu of the paper stamp now used and as described in the present specifications and illustrated in the accompanying drawings.

Heretofore numerous attempts have been made to design a machine of this character which would comply with the requirements of the laws governing the use of such a press and especially with respect to prevent its surreptitious or fraudulent use; the principal object of my invention is to provide a relatively simple, compact, and durable machine, embodying the requisite functional characteristics aforesaid, in which impressions that have not been paid for cannot be made, and in which false records or readings of meters cannot be hidden, or which cannot be fraudulently adjusted or tampered with even by custodians of the keys to the press, without leaving evidence thereof.

From a functional or mechanical viewpoint, another object of my invention is to provide in such a press a yieldable platen that will provide an automatic "make ready" and thus produce a distinct impression on matter of varying thickness and uneven surface.

Another object of my invention is to provide concealed and inaccessible printing or stamping type at all points of its movement during the action of making the impression and receding same to initial position, thus rendering it impossible to make an impression with the printing type without registering its movement.

My invention is further characterized by providing automatic means for controlling the movement of the printing mechanism during the descent and elevation of the printing type so that neither movement can be reversed when started until the complete cycle of movement in either direction is completed.

A further object of my invention is to provide a means to supply ink to the type of said press in such a way that great numbers of impressions may be made without manual effort or attention, and for this purpose I have supplied a ribbon carrying ink and mounted on spools, which spools are rotated automatically by the printing arm

operation, winding and unwinding the ribbon its full length, and to automatically reverse the direction of travel of the ribbon at either end of its length, thus supplying ink to the type continually until all of the ink has been absorbed or the ribbon worn out, and means to quickly and easily re-ink said ribbon or replace said ribbon when worn out.

A further object of my invention is to provide in a press of the character stated, a total adding meter co-operating with the printing mechanism, adapted to successively count and register the total number of impressions made by said printing mechanism, and a downward count meter actuated in conjunction with said printing mechanism and simultaneously with said total adding meter, said downward count meter adapted to count off the number of impressions for which the press has been set and which may be re-set for a predetermined number of impressions.

My invention has for a further object the provision of means for re-setting the downward count meter for an additional predetermined number of impressions, access to said resetting means being sealed by a seal which must be destroyed before the resetting operation may be effected.

With the foregoing and other objects in view which will appear more fully as the description proceeds, my invention resides in the novel combination and arrangement of co-operating elements, claimed and shown in the accompanying drawings forming a part of the present application, and in which—

Fig. 1 is a top view of the entire mechanism of the machine above the base plate.

Fig. 2 is a view from the rear of the entire mechanism of the machine including sections of the enclosing cases.

Fig. 3 is a view from the right of the front half of the mechanism of the machine in normal position.

Fig. 4 is a view from the right of the back half of the mechanism of the machine in normal position and also a partial view of the enclosing cases.

Fig. 5 is a sectional view of the seal used to protect the locks of the mechanism.

Figs. 5^A-5^B-5^C are detail views relating to the seal.

Fig. 6 is a view from the left of the front

half of the mechanism in normal position showing sections of the enclosing cases.

Fig. 6^A is a sectional view from the front showing the printing arm, printing member, 5 type, and the dater.

Fig. 6^B is a cross section of the printing member and type.

Fig. 7 is a view from the left of the back 10 half of the mechanism in normal position showing sections of the enclosing cases.

Fig. 7^A is a detail view, partly broken away, of the mechanism that controls the up and down movement of the printing arm during a printing operation.

Fig. 8 is a view from the left of the back 15 half of the machine in printing position, also showing sections of the enclosing cases.

Fig. 9 is a view from the right of the front 20 half of the mechanism in printing position, also showing sections of the enclosing cases.

Fig. 10 is a partial view from the right of the ribbon control; the broken lines of this figure show the ribbon control in reverse position.

Fig. 11 is a partial view from the right 25 showing sections of the locking mechanism; the broken lines of this figure show the same mechanism in unlocked position.

Fig. 12 is a partial view from the left of 30 the cover locking mechanism.

Fig. 13 is a partial view from the front of the said locking mechanism.

In all of the views or figures in which reference is made to right or left or other relative positions, all such references are based 35 on the fact that the platen opening hereinafter referred to under 137, and most clearly shown in Fig. 3, is located in the front of the said mechanism; like numbers designate like parts.

20 is the base plate to which the entire mechanism of the machine is secured. In bearings 21, mounted on said base plate 20, is rockably mounted the operating shaft 22, 45 which shaft 22 operates and actuates all of the printing mechanism, and is most clearly illustrated in Figs. 1 and 2; rigidly mounted upon shaft 22 are the guard member arm cams 23, these cams 23 operating under rollers 24 to actuate guard member arms 25, which are tensioned by springs 25^A, which guard member arms, rollers, and cams, are most clearly shown in Figs. 1, 2 and 4 in normal position, and Fig. 8 showing the same 50 in printing position; guard member arms 25 rock on center bearing shaft 26, which center bearing shaft 26 rests in bearings 27 which rest upon and are secured to base plate 20, as shown in Figs. 4 and 7. Guard member arms 25, operated by cams 23, extend to and are permanently fastened to the guard member 28, which member operates as 55 shown in Figs. 3, 6 and 9.

Also mounted upon operating shaft 22, be-

tween cams 23, is the actuating lever 29, connected through links 30 to printing arm 31, which is mounted upon and above and rocks upon center bearing shaft 26; the actuating lever 29, links 30, and printing arm 31, are most clearly shown in Figs. 1, 2 and 7 in normal position and Fig. 8 in printing position; printing arm 31 is fastened to and actuates the printing member 32, their action is best understood by reference to Figs. 1, 3 and 6, in which they are shown in normal position, and Fig. 9 which shows them in printing position, the guard member 28 being drawn in full and the printing member 32 being shown by broken lines.

Also attached to the left end of the operating shaft 22 is a U-shaped ratchet dog operating hanger 33; attached to this hanger 33 are ratchet dogs 34 and 34^A, which are held in hanger 33 by pin 35, and said dogs 34 are held in tension by spring 36; and attached to the side of the dogs 34 are trip pins 37, which are operated by the T-shaped trip bar 38 having central T-arm 38^A, which is mounted on the inside of the U-shaped hanger 33 by pin 39. The lower end of bar 38 is controlled by the two permanent pins 40, 40^A mounted in the fixed ratchet 41, which is permanently secured to base plate 20 and through the center of which passes the operating shaft 22; also attached to trip 38 is spring hanger 42, to the free end of which is attached tension spring 43, which is also attached to U-shaped hanger 33 by pin 44. All of the numbers heretofore mentioned in this paragraph are best shown in assembly 45 from the rear, as shown in Fig. 2, from the top, as shown in Fig. 1, from the left side, as shown in Fig. 7 in normal position, which show dog 34 engaged against ratchet 41, held in tension thru pin 37 and trip bar 38 by spring 43, said spring 43 being past center in this position of the mechanism; Fig. 8 shows the same parts in the position they assume when the entire mechanism is 50 in printing position and shows the position of dogs 34, trip bar 38, spring hanger 42, after pin 40 has engaged the arm 38 of the T-shaped trip bar 38 and forced the spring 43 past the center of 33, opposite to the position shown in Fig. 7; the dogs 34 are now 55 in position to engage the ratchet 41 on the return movement of the printing arm and thus prevent the printing arm being moved in the opposite direction, thus making it impossible to remove any matter from the press 60 until the impression has been fully made and recorded, so that the mechanism can only print upon one piece of matter at one time and must be returned to normal position before the matter so printed upon and recorded can be removed from the press.

Actuating lever 29, attached to operating shaft 22, also connects with and operates

plunger 45 by means of pin 46, plunger 45 operates within air bumper cylinder 47, which cylinder 47 is movably connected by hinge 48 to plate 49, which plate is permanently fastened underneath the platen spring support plate 50, which support plate 50 is permanently fastened to base plate 20, and this actuating lever 29 is also connected to plate 49 by tension springs 51; actuating lever 29, plunger 45, cylinder 47, and tension springs 51, and their connections, are best shown in the normal position in Fig. 7, and in printing position in Fig. 8, the front end of cylinder 47, springs 51, hinge 48, plate 49, plate 50, and their relative positions, are best shown in Fig. 6 in normal position, a rear view of actuating arm 29 and its connections is best shown in Fig. 2. The function of air bumper cylinder 47 is to restrain the recoil action of the various springs which are placed under tension when actuating lever 29 completes its working motion and is released, thus saving the entire mechanism from the jar and percussion that would result if the air bumper cylinder were not provided.

Platen spring support plate 50 holds springs 52 in place against platen plate 53, said platen plate 53 sets in opening 54 in base plate 20, and is held in position, and when in action, its movement is limited by platen plate stops 55, which are attached thereto; platen plate 53 is faced on its upper side with a cushion 56, preferably of sponge rubber or similar material. Platen plate 53 and its component parts as above set forth in this paragraph, are best shown in Figs. 3, 6 and 9, the platen plate 53 resting in platen plate opening 54, as shown in Fig. 3; the relative positions of guard box 28, printing member 32, platen plate 53, when in printing position, are best shown in Fig. 9, this platen plate 53 being thus constructed with a face of sponge rubber or similar material, and tensioned by springs 52, automatically adjusts itself so that it produces a uniform pressure on different thicknesses and irregular surfaces of matter upon which the indicia is to be printed, thus printing uniform legible indicia. The movement of the platen, which yields at one side, or one corner, or one end more than at the other side, or corner, or end to compensate for a difference in the thickness of the matter being printed at such point, I term a variable movement.

To guard member 28 is held type protecting shield 57 by means of pin 58, this protecting shield 57 is most clearly shown in normal position in Fig. 3, and in printing position in Fig. 9. When in normal position, this protecting shield 57 covers the face of the type 60 and makes it impossible for an impression or indicia to be made either by the use of the mechanism, or by tampering, or by an upward pressure, of any matter

against the face of the type until the said protecting shield has been automatically removed from the face of the type in the course of the regular printing operation.

Printing member 32 has passing through it date type holder 59, to the lower end of which is attached interchangeable type 59^a; this holder 59 is contained within a tube 59^b, permanently attached to the printing member 32 and covered with a screw cap 59^c, making it accessible to change the date of the type at any time. Permanently attached to the lower face of the printing member 32 is type 60, with which to print, the major portion of which type can only be removed from the printing member by partly dismantling the press, it being necessary to remove shaft 26 and raise printing arm 31 out of the guard member 28, which gives access to the said type 60. When printing member 32, together with the type 60, is in normal position in the press, it is completely enclosed on all four sides by the guard member 28 and is covered on its lower face by protecting shield 57, on top by printing member 32, thus making it impossible to gain access to the type without partially dismantling the press, but permits free use of type 60 in full normal operation of the press.

Attached to guard member arms 25 are the various members operating and controlling the type inking ribbon 61, which consist of parts as follows: Bearing arms 62, which carry stops 62^a and are attached to guard member arms 25 and which carry the ribbon spools 63, and through ribbon spools 63 and the arms 62 pass shafts 64, which are permanently fastened to said spools 63, and to the right end of shafts 64 are fastened ratchet wheels 65, and to the left end of shaft 64 are fastened brake tension wheels 66, which are held under tension by the spring brake 67; ratchet wheels 65 are operated by ratchet pawls 68, which are suspending from rocking arms 69 by pins 70 and held under tension by springs 71, and rocking arms 69 are connected together and held under tension by spring 72; the action of pawls 68 and rocking arms 69 are both controlled by the automatic ribbon actuating block 73, which rides on guide shaft 74; block 73 is operated by bar 75, which is connected by links 76 to guide shaft 74, and said bar 75 is held under tension by spring 77, and the guide shaft 74 passes through bearings 78, which are fastened to right hand guard box arm 25. Fig. 3 shows the above described parts of the ribbon control in a normal or non-printing position with block 73 resting against rear pawl 68, which in this position is engaged with rear ratchet wheel 65 to wind ribbon upon rear spool 63. Fig. 9 shows the same parts of the ribbon control with the mechanism in printing position and shows block 73 at the forward point 130

of its movement when winding the ribbon upon the rear spool, as above described, showing rear rocking arm 69 in the forward position resting against stop 62^A, thus placing rear pawl 68 in the forward engaged position against rear ratchet 65, the tension for these two ribbon spools 63 is the brake 67, illustrated in Fig. 6; Fig. 10 shows the block 73 in a position to wind the ribbon upon the forward spool 63 and is standing in the normal or non-printing position with forward rocking arm 69 and forward pawl 68 in normal position, and shows by broken lines the position of pawl 68 when it is moved forward at the full stroke of the mechanism during the printing operation, at which point it has moved the forward ratchet wheel 65 and forward spool 63 part of a revolution, sufficient to wind a portion of the ribbon 61 thereon. This Fig. 10 further shows the relative positions of links 76 when the block 73 is in the winding position above described, and in broken lines shows the links 76 in the position occupied when the block 73 is operating rear ribbon spool 63. It will thus be seen that the means for actuating the said pawl mechanism to successive advance and automatic reverse of the ribbon is accomplished by the members as set forth in the foregoing part of this paragraph, and that the action which takes place is as follows: When the ribbon moving in either direction has unwound its full length from one spool to the other, or is subjected to an abnormal tension, one of pawls 68, which is in contact with actuating block 73, will prevent the movement of the said block 73, which will subject, through arm 75, a pressure upon links 76, thus reversing their position relative to guide bar 74 and forcing guide bar 74 to cause block 73 to exert pressure against the opposite pawl, thus reversing the direction in which the ribbon spools are travelling. Guide shaft 74 is operated through curved pin 79 and arm 80, and shaft 81 and connecting links 82, which are connected to the rear end of and operated by printing arm 31. Fig. 4 shows the rear end of guide shaft 74, its rear bearing 78, and its connection to links 76, and the spring 77 connected to base plate 20, which holds them under tension and which, when the ribbon control mechanism is reversed, is passed over center and holds links 76 under the same tension in the opposite position. The position shown in Fig. 4 of these parts represents the machine in normal position and the ribbon control operating to wind on the rear spool, as shown in Fig. 3. Fig. 4 further shows the connection of guide shaft 74 by pin 79, which loosely couples arm 80; Fig. 2 shows the connection of arm 80 with shaft 81, as also does Fig. 1. Links 82 connecting shaft 81 to printing arm 31 are shown in Figs. 1, 2 and 4, the forward and

backward movements of guide shaft 74 are controlled and operated entirely by printing arm 31 through the above described connections, thus completing the mechanical action of the ribbon control and the reverse thereof. 76

Nos. 83 to 113 inclusive show the various parts of the automatic locking mechanism by which the press is locked against surreptitious or unlawful use and the releasing mechanism of the said locking mechanism; 75 83 being the master lock working on the left of printing arm 31 and 84 being an auxiliary lock operating on the right of said arm 31; the locks 83 and 84 are pivoted by pin 85 to block 86 attached to base plate 20, 80 and are held under tension by spring 87, which is attached to post 88, which is fastened to base plate 20; this spring 87, by means of a connecting pin 89, acts as a tension spring to pull lock 83 and auxiliary lock 84 into locked position against pin 84^A which passes through and projects out on either side of printing arm 31, as shown in Fig. 11. Attached to and part of lock 83 is trip arm 90, which is confined and released by trip 91, and this trip 91 moves on movable arm 92, which arm 92 is fastened through the frame of the downward count meter 93 by pin 94, and movable arm 92 is held down by spring 95, and said movable arm 92 has a stop 96 which rests on the downward count meter bed plate 97; the downward count meter 93 is operated by arm 98, connected to and actuated by printing arm 31, which, through connecting rod 99, rocks shaft 100, which passes through the downward count meter and rotates index wheels 101, which wheels have cross slots 102. The said cross slots 102, and all other parts mentioned in the foregoing part of this paragraph, are best shown in Figs. 1, 2, 7, 8 and 11. Fig. 11 shows in full drawing lock 83, together with arm 90, trip 91, slots 102 in indice wheels 101 of downward count meter 93 in the locked position; in broken lines are shown the positions of the same parts in normal or unlocked position. When index wheels 101 have revolved to the limit of the number of impressions to be recorded, slots 102 come into alignment in such a position that the face of trip 91 drops into the said slots 102, thus releasing arm 90 and allowing locks 83 and 84, under the tension of spring 87, to drop into the locked position so as to engage pin 84^A, as shown in the said Fig. 11, thus making it impossible to further operate the machine to produce, or print, until the machine has been properly and lawfully re-set. Shaft 100 also operates in reverse by the re-setting mechanism 125 through sprocket wheel 103 attached to the left end of said shaft 100, which sprocket wheel is driven by continuous link chain 104, which in turn is driven by sprocket wheel 105, which is rotated by shaft 106, which 120

rides in bearings 106^A; fastened to base plate 20; and the said shaft 106 is actuated through key lock 107; on shaft 106 is rigidly fastened cam 108, which when shaft 106 is rotated 5 pushes down rod 109 which is directly connected to and a part of lock 83. Fig. 11 shows the relative positions of shaft 106, cam 108, and rod 109, the action produced in rotating shaft 106, which turns cam 108, 10 pushing down rod 109 to the position shown by the broken lines of this Fig. 11, resets locks 83 and 84 and arm 90 to the position shown by the broken lines, as explained heretofore. Mounted on shaft 106 is a non-reversible ratchet wheel 110, and engageable to this ratchet is spring pawl 111, which is fastened by screw 112 to base plate 20, thus making it impossible to reverse the reading of the downward count meter without unlocking lock 107, which can only be done by breaking the seal 107^A. The action of rotating shaft 106 through lock 107 revolves sprocket 105 and drives chain 104, revolving sprocket 103 and shaft 100 in downward 25 count meter 93, to which shaft 100 are fastened the index wheels 101; this revolving action takes place simultaneously with the movements before described of cam 108 and rod 109; and thus by rotating index wheels 30 101 place them with their numbers in the original recording position and remove reset slots 102 to their inactive or non-functioning position, thus disengaging them from trip 91; trip 91 being under the tension of spring 95 has resumed its normal position where it has engaged arm 90 immediately upon its being actuated to normal position by cam 108. In the foregoing description as set forth in this paragraph of the action of 35 the re-setting mechanism, shaft 106, sprocket 105, chain 104, sprocket 103, shaft 100, trip 91, trip arm 92, trip arm pin 94, trip arm spring 95, are best shown in Fig. 7 in normal position; the relative position of cam 108 to sprocket 105, shaft 106, and non-reverse ratchet 110, is best shown in Figs. 7 and 8, while the relative position of cam 108 and shaft 106 to the other parts of the locking mechanism are best shown in Fig. 11, 40 which also illustrates the various positions of bar 109, lock 83, arm 90, trip 91, index wheels 101 and slots 102 in downward count meter 93, which is supported as shown on post 113.

45 The total add meter 114, which perpetually records the number of impressions made by the printing mechanism, is actuated directly from the printing arm 31 by connecting rod 115, connected to arm 116, which rotates index wheels 117, and the said meter 114 is set on a post 118, secured to base plate 20; these parts Nos. 114, 115, 116, 117, and 118 are best illustrated in Figs. 1, 2 and 4. This total add meter 114 records one by 50 one each impression as made, the number of

impressions made by operating arm 116, and thus provides an accurate method of determining the total number of impressions made by the printing mechanism.

55 Base plate 20 rests on legs 119, which are permanently fastened thereto, and base plate 20 has corner guides 120 which fit into the corner of lower case 121, which case fits securely against base plate 20, and is fastened thereto by screws 122 projecting through base plate 20 and screwing into lugs 123 in bottom of case 121, and having their heads confined within the upper lock case 124, which securely encloses all of that part of the mechanism which rests above the base plate 20 and to the rear of the accessible parts of the mechanism which are shown in Fig. 3; said case 124 is provided with guarded ports through which guard box arms 25, printing arm 31, guide shaft 74 and shaft 81 project into the section which is accessible as shown in Fig. 3; case 124 has slotted projections 125 at the bottom of said case which pass through holes 126 in base plate 20 and the slots 127 in said projections 125 engage spring keys 128, which are movably secured to the bottom of base plate 20 and operated by key lock 129 through crank shaft 130, supported on bearings 131, and operating tension bars 132, which hold spring keys 128 in position by springs 133 riding against hangers 134. This lock case 124 is provided with a seal device 107^A over lock 107, as shown in Fig. 5. The operation of unlocking and removing lock case 124 provides access to the parts of the machine located above the base plate 20 and best shown in Figs. 4 and 7, and also provides access to center bearing shaft 26 and type bar 31, which must be removed, as hereinbefore described, to gain access to the type 60; the removal of lock case 124 further provides access to the heads of screws 122, which when removed, allow lower case 121 to be removed, providing access to all of the parts located below base plate 20; thus is provided by and in the said lock case 124 an effective means of preventing any person from obtaining access to the parts of the mechanism contained therein during such time as the said case may be locked and the lock protected by the seal 107^A.

60 Over and above and completely surrounding all of the mechanism above base plate 20, including the lock case 124, is outer case 136, which is provided on the front end with the platen opening 137, through which matter may be placed in position to receive impressions. At the point immediately back of platen 53 is the guide plate 138, against which any matter to be printed may rest, and these parts heretofore mentioned in this paragraph are most clearly shown in Fig. 6.

65 An opening 139 is provided on the right 120

side of lock case 124 and a corresponding opening 140 in outer case 136, through which an actuating means may pass to engage and operate shaft 22, operated either by manual or mechanical power.

Fig. 5 illustrates a closure for the key operated lock 107 and the closure so formed carries a seal 107^a, said seal is held between the externally threaded tubular boss 107^c 10 and the internally threaded cap 107^d positioned to close the window 107^b in cap 107^d. Said cap is provided with an annular ratchet 107^e on the inner face thereof with which the yieldable pin 107^f is engaged, being held in engaged relation by the coil spring 107^g. For releasing purposes a pin 107^h extends from the yieldable pin 107^f, traveling in slot 107ⁱ, into opening 107^j, to be engaged by the end of a key or similar instrument. To insert a key in lock 107 the seal 107^a must first be broken and removed, after which the custodian of the key to lock 107 may recede the pin 107^h and disengage the yieldable pin 107^f from the ratchet 107^e integral with the cap 107^d which cap may then be unscrewed from the tubular boss 107^c; and for the purpose of again sealing lock 107 another seal 107^a is substituted for the broken seal and the cap 107^d is again screwed on the tubular boss 107^c and is automatically locked by said ratchet and yieldable pin. It will be observed that when the printing arm 31 is being moved to effect a printing operation, dog 34 engages ratchet 41 and prevents arm 31 from backward movement until the printing operation is done. At this time bar 38 engages pin 37. As soon as a print has been made arm 38^a engages pin 40 and causes the lower end of spring 43 to pass to the other side of 33 thereby causing arm 42 to disengage dog 34 from ratchet 41 and at the same time spring 36 causes dog 34^a to engage ratchet 41. The printing arm is then permitted to go back to its upper position but dog 34^a holds it from downward movement until the upper position is reached, at which time arm 38^a engages pin 40^a and dog 34^a is thrown out of engagement with ratchet 41 and dog 34 into engagement with ratchet 41.

Lower case 121 is provided with a seal 107^a (hereinbefore referred to) only through which access can be had to lock 129.

Outer case 136 and lock case 124 are provided with openings 141, through which both the downward count and total add meters may be read.

From a perusal of the foregoing description in conjunction with the annexed drawings it is obvious that I have provided a printing press particularly adapted for printing letters, missives, and matter in general, which will accurately register each impression made and which will positively preclude operation of the mechanism without

registration of each printing operation upon both the total add and downward count meters.

By provision of the downward count meter adjusting and controlling instrumentalities in the manner set forth, the same can only be re-set by the custodian of the keys provided for re-setting the same, and who is authorized to break the seal covering the lock on which said keys operate.

What I claim as new is:

1. In combination, a printing means; a printing arm therefor; means for actuating said printing arm to lower said printing means for printing purposes and for alternately elevating the same; and means operating coordinately with said printing means for holding the matter being printed to prevent removal of the same and the insertion of other matter during one printing operation.

2. In combination, printing means; a printing arm therefor; means for actuating said printing arm to lower said printing means for printing purposes and alternately elevate the same; and means operating coordinately with said printing means to securely hold the matter to be printed prior to descension of said printing means and during the printing operation to prevent removal of the matter and insertion of other matter during one printing operation.

3. In combination, printing means; a printing arm therefor; means for actuating said printing arm to lower said printing member for printing purposes and alternately elevate the same; and means operating in unison with the travel of and ahead of said printing means to grip and hold the matter to be printed prior to and during the printing operation to prevent removal of the same and insertion of other matter during one printing operation.

4. In combination, printing means; a printing arm therefor; matter holding means operating coordinately with said printing means; means for actuating said printing arm and matter holding means to lower said printing means and said matter holding means for printing purposes and hold the matter being printed during the printing operation to prevent removal of the same and insertion of other matter during one printing operation and alternately elevate and lower said printing means and matter holding means during completion of the printing operation.

5. In combination, a printing means; a printing arm therefor; matter holding means operating coordinately with said printing means; means for actuating said printing arm and matter holding means to lower said printing means for printing purposes and advance said matter holding means at a greater ratio with respect to the travel of

1. Said printing means to grip and hold the matter to be printed and for holding the same during the printing operation to prevent said matter from being removed and the insertion of other matter during one printing operation, and alternately elevate said printing means in advance of and simultaneously with the elevation of the matter holding means. 70
2. In combination, printing means; a printing arm therefor; means for actuating said printing arm to lower said printing means for printing purposes and for alternately elevating the same; means operating 75
3. coordinately with said printing means for holding the matter being printed to prevent removal of the same and insertion of other matter during one printing operation; and means for preventing elevations of said 80
4. printing means during the descension of said printing means. 85
5. In combination, printing means; printing arm therefor; means for actuating said printing arm to lower said printing means for printing purposes and to alternately elevate the same; means operating in conjunction 90
6. with said printing means for holding the matter being printed to prevent removal of same and insertion of other matter during 95
7. one printing operation; and means for preventing reversing the movement of said printing means before completion of the movement of the printing arm after commencement of the stroke and before an impression is made. 100
8. In combination, printing means; printing arm therefor; means for actuating said printing arm to lower said printing means for printing purposes and for alternately elevating the same; means operating in conjunction with said printing means for holding the matter being printed to prevent removal of the same and insertion of other matter during one printing operation; and means for preventing the descension of said printing means after commencement of the elevation thereof. 105
9. In combination, printing means; a printing arm therefor; means for actuating said printing arm to lower said printing means for printing purposes and alternately elevate the same after an impression has been made; a total add meter operating in unison with the actuation of said printing 110
10. arm for counting and recording the total number of impressions made by said printing means; and means operating in conjunction with said printing means for holding the matter being printed during the printing operation and to prevent removal of the matter and insertion of other matter during one printing operation to prevent the possibility of making more impressions than are registered on said meter. 115
11. In a device of the character described, a printing arm; means to cause the downward movement of said arm; means to prevent the upward movement of said arm until a full travel downward of said arm has been made; means to cause the upward movement of said arm after the downward travel thereof has been completed; and means to prevent the downward movement of said arm until the full upward movement thereof has been completed; in combination with a down count meter; and means operated by the means that operates the printing arm, whereby the full downward movement of said printing arm effects the operation of the meter. 120
12. In combination, printing means; a printing arm therefor; means for actuating said printing arm to lower said printing means for printing purposes and alternately elevate the same; a downward count meter actuated in unison with the operation of said printing means for indicating the number of impressions remaining to be made by said printing means; and means operating in conjunction with said printing means for holding the matter being printed during the printing operation to prevent removal of the same and insertion of other matter during one printing operation to prevent the possibility of printing matter without counting off the impression on said downward count meter. 125
13. In combination, printing means; a printing arm therefor; means for actuating said printing arm to lower said printing means for printing purposes and alternately elevate the same after an impression has been made; the downward count meter; and means operating in conjunction with said printing means to prevent elevation of said printing means during descension thereof before completion of that respective printing operation to prevent registration of more than one impression on said downward count meter when only one impression is made. 130
14. In combination, printing means; a printing arm therefor; means for actuating said printing arm to lower said printing means for printing purposes and alternately elevate the same after an impression has been made; a guard member adapted to hold 135

the matter being printed against movement during the printing and recording operations; a total add and a downward count meter; and means for actuating both said meters in unison with the actuation of said printing arm to record the number of impressions made and to be made by said printing means.

15. In combination, printing means; a printing arm therefor; means for actuating said printing arm to lower said printing means for printing purposes and alternately elevate the same after an impression is made; a guard member adapted to hold the matter being printed against movement during the printing and recording operations; a total add meter co-operating with said printing arm and means for counting and recording the total number of impressions made by said printing means; a downward count meter adapted to be set for a predetermined number of impressions, co-operating with said printing means for indicating the number of impressions that may be made before completion of that respective number of impressions for which said downward count meter was set; and key operated means for re-setting said downward count meter upon completion of said predetermined number of impressions for another predetermined number of impressions.

16. In combination, printing means; a printing arm therefor; means for actuating said printing arm to lower said printing means for printing purposes and alternately elevate same after an impression has been made; a guard member adapted to hold the matter being printed against movement during the printing and recording operations; a downward count meter adapted to be set for a predetermined number of impressions; means for co-operating said downward count meter with said printing arm to successively indicate the number of impressions remaining to be made thereby; mechanically operated means for resetting said downward count meter upon completion of the predetermined number of impressions for which it was set; and means for locking said downward count meter; and means to prevent unauthorized or surreptitious resetting of said downward count meter.

17. In combination, printing means; a cover enclosing said printing means; a lock for said cover; a printing arm therefor; means for actuating said printing arm to lower said printing means for printing purposes and alternately elevate the same after an impression has been made; a guard member adapted to hold the matter being printed against movement during the printing and recording operations; and means for locking and sealing said locking means to prevent the surreptitious or fraudulent resetting of the downward count meter without leaving

indications of such surreptitious or fraudulent resetting.

18. In combination, printing means; a printing arm therefor; means for actuating said printing arm to lower said printing means for printing purposes and alternately elevate the same after an impression is made; a guard member adapted to hold the matter being printed against movement during the printing and recording operations; a downward count meter adapted to be set for a predetermined number of impressions; means co-operating said downward count meter with said printing arm to actuate the same in unison therewith to register the number of impressions that may yet be made by said printing means; and means for automatically locking said downward count meter upon the exhaustion of the predetermined number of impressions for which it was set and prevent continued action of said printing arm without first re-setting said downward count meter.

19. In combination, printing means; a printing arm therefor; means for actuating said printing arm to lower said printing means for printing purposes and alternately elevate the same after an impression has been made; a guard member adapted to hold the matter being printed against movement during the printing and recording operations; a downward count meter adapted to be set for a predetermined number of impressions; means co-operating said downward count meter with said printing arm to actuate the same in unison therewith to register the number of impressions yet to be made by said printing means; means for automatically locking said downward count meter upon completion of the predetermined number of impressions for which said downward count meter was set to prevent continued actuation of said printing arm without first resetting said downward count meter; key operated means for releasing said automatic downward count meter locking means; and means for locking said releasing means to prevent unauthorized resetting or adjustment of said downward count meter.

20. In combination, printing means; a printing arm therefor; means for actuating said printing arm to lower said printing means for printing purposes and alternately elevate the same after an impression has been made; a guard member adapted to hold the matter being printed against movement during the printing and recording operations; a downward count meter adapted to be set for a predetermined number of impressions; means for actuating said downward count meter in unison with said printing arm to indicate the number of impressions that may yet be made by said printing means; means for automatically locking said downward count meter upon completion of

the predetermined number of impressions for which it was set to prevent continued actuation of said printing arm simultaneously with the automatic locking of said downward count meter; means operable by the custodian of the keys to the machine for releasing said automatic locking means.

21. In combination, printing means; a printing arm therefor; means for actuating said printing arm to lower said printing means for printing purposes and alternately elevate the same after an impression has been made; and a yieldable platen disposed beneath said printing means against which said printing means is adapted to bear when an impression is made by said printing means, in combination with a guard member adapted to hold the matter being printed until the printing operation is completed and to position the platen.

22. In a device of the character described, a rockably yielding platen in combination with a guard member adapted to position the platen with reference to the surface to be printed upon.

23. In combination, an oscillatable printing type supporting arm; printing type mounted thereon; a resilient yieldable platen; means to operate the arm to lower said printing type to said platen in combination with a guard member adapted to force said platen to align with said printing type to provide a legible impression.

24. In combination, printing means; a base plate; a rockably mounted printing arm on said base plate; means for actuating said printing arm to lower said printing means for printing purposes and to alternately elevate the same after an impression has been made; a variable resilient yieldable platen mounted on said base plate; and means to supply ink to said printing means.

25. In combination, printing type; an oscillatable printing arm for supporting said printing type; means for oscillating said printing arm to lower said printing type to make an impression and alternately elevate same; a guard member surrounding said printing type; supporting guard member arms for said guard member; ribbon spools carried by said guard member arms; a ribbon carried by said ribbon spools extending beneath and against said printing type; and means actuated in unison with the operating of said printing type supporting printing arm for successively advancing said ribbon.

26. In combination, printing means; a support therefor; an oscillatable printing arm carrying said printing type and support; a guard member surrounding said type; oscillatable arms for said type guard member; dual ribbon spools supported by said guard member oscillatable arms; a ribbon wound about said spools extending be-

neath said printing type; means co-operating the printing type supporting oscillatable arm aforesaid with said ribbon spools to advance said ribbon upon each impression made by said printing means; and means for automatically reversing the direction of travel of said ribbon when the same is substantially completely wound from one of said spools to the other.

27. In combination, printing means; an oscillatable printing arm for said printing means; a guard member surrounding four sides of said printing means; oscillatable arms for said guard member; means for actuating said printing means supporting arm and guard member supporting arms in unison for advancing said guard member ahead of said printing means to grip and hold the matter previous to and during the printing operation to prevent removal of the same and insertion of other matter during one printing operation.

28. In combination, a base; printing means; an oscillatable printing arm for said printing means rockably mounted on said base; a guard member surrounding said printing means; oscillatable arms for said guard member rockably mounted on said base; an actuating shaft linked to said printing mechanism supporting arm adapted to alternately elevate and lower the same for printing purposes and cams on said actuating shaft for oscillating said guard member supporting arms and for lowering the same in advance of said printing means to grip and hold the matter to be printed to prevent removal of same and insertion of other matter during one printing operation.

29. In combination, a base; printing mechanism mounted on said base; an inking ribbon for said printing mechanism; a total add meter co-operating with said printing mechanism adapted to successively count and record the number of impressions made by said printing mechanism; a downward count meter co-operating with and controlling the actuation of said printing mechanism adapted to be set for a predetermined number of impressions and stop said printing mechanism when said predetermined number of impressions have been made; means for resetting said downward count meter; a casing enclosing said downward count meter resetting means permanently secured to said base; a casing enclosing said printing mechanism co-operating with said downward count meter.

30. In combination, a base; printing mechanism mounted on said base; an inking ribbon for said printing mechanism; a total add meter co-operating with said printing mechanism adapted to successively count and record the number of impressions made by said printing mechanism and actuated in unison with a downward count meter;

- means to prevent the upward movement of the printing mechanism until the full downward movement of the same has been effected; and a locked casing for said printing mechanism comprised of sections adapted to be fastened together comprising a whole casing enclosing the functional mechanism of said press; and means to lock said cases against separation by unauthorized agencies.
31. In a printing press of the character described, a base plate; a printing arm rockably mounted on said plate; printing means mounted in said arm; and means to guard the printing means during the printing operations, said guard means being adapted to hold the matter being printed upon against removal until the printing thereon is done.
32. In combination in a printing press, a guard member, a type member enclosed and rendered inaccessible thereby, and a removable type holder mounted within the type member.
33. In a printing press, in combination, a guard member; a type member enclosed therein and rendered inaccessible thereby; a removable type holder mounted within the type member; a type protecting shield mounted on said guard member adapted to cover the type holder until removed from in front thereof; means to operate said shield to unclog the type after the guard member is positioned to hold the matter being printed; and means to operate the guard member to hold the matter being printed upon.
34. In a printing press of the character described, a base plate; printing operating means mounted on said plate; an outer case locked to said base; an inner case within said outer case independently locked to said base, said inner case enclosing the printing operating means; and means to operate said printing operating means while said inner case is locked.
35. In a printing press a base plate, printing mechanism mounted on said plate, a case adapted to enclose said printing mechanism, means to lock said case to said base, a total add meter and a downward count meter mounted on said base and within said case; means to seal said locking means, means to operate said printing means acting in coordination with said printing means to actuate said meters, and means to prevent the return of said printing means until after a printing operation has been completed.
36. In a printing press a base plate, a case mounted upon the top thereof, printing and metering means mounted on the top of said plate; means to lock said top case to said plate, means to operate said printing and metering means in coordination whereby a predetermined number of printing operations may be registered by said metering means, means to lock said printing means when the number of operations have been accomplished; a bottom case secured on the under side of said base plate, said last locking means being contained within the top case and being inaccessible until the top case is unlocked.
37. In a printing press of the character described the combination of a printing member with a rockably mounted guard member, said guard member surrounding four sides of the printing member in close proximity thereto and rendering the same inaccessible during the printing operation.
38. In a printing press of the character described the combination of a printing member with a guard member and a shield mounted therein said guard member and shield surrounding said printing member and rendering the same inaccessible when the printing member is not being operated.
39. In a printing press of the character described, a base; a stationary ratchet mounted on said base; an actuating shaft journaled in said ratchet; a hanger arm rigidly mounted on said shaft adjacent to said ratchet; oppositely projecting spring pressed dogs rockably mounted on said hanger arm, adapted to alternately engage said ratchet, one of said dogs engaging the ratchet during the entire movement of the actuating shaft in either direction; and means to operate said dogs.
40. In a printing press of the character described, a base; a stationary ratchet mounted on said base, a portion of the face of said ratchet being the segment of a circle and provided with teeth; an actuating shaft rockably mounted in said ratchet; a hanger arm rigidly mounted on said shaft adjacent to said ratchet; a pair of spring pressed dogs rockably mounted on said arm; and means to alternately cause one of said dogs to engage said ratchet and the other dog to disengage from said ratchet during the entire movement of the actuating shaft in either direction.

In witness that I claim the foregoing I have hereunto subscribed my name this 20th day of June, 1925.

RALPH G. WHITLOCK.
